UNITED STATES PATENT OFFICE.

JAMES M. PORTER, OF SPRINGDALE, PENNSYLVANIA.

MECHANICAL STOKER.

Application filed October 28, 1920. Serial No. 420,236.

To all whom it may concern:

Be it known that I, JAMES M. PORTER, a citizen of the United States, and resident of Springdale, in the county of Allegheny and State of Pennsylvania, have invented a new and useful Improvement in Mechanical Stokers; and I do hereby declare the following to be a full, clear, and exact description thereof.

10 My invention relates to stokers for firing boilers, stills or other steam generating apparatus and it has for its object to provide a mechanical stoker of improved construction which shall be economical in operation and which shall not require the attention of a skilled operator. In addition, my invention aims to provide a stoker which may be constructed as a self-contained unit which can be readily removed from one furnace and applied to another. This makes it possible to use my improved stoker with any one of a battery of furnaces, thus producing a considerable saving of equipment.

In the accompanying drawing, Fig. 1 is a side elevational view showing an automatic mechanical stoker constructed in accordance with my invention; Fig. 2 is a longitudinal sectional view taken centrally through the machine on the line 2—2, Fig. 3; Fig. 3 is a transverse sectional view taken approximately on the line 3—3, Fig. 2; and Fig. 4 is a detail view showing the grate bar construction.

In the drawings the numeral 2 designates 35 side plates which carry the power mechanism of the machine and are supported on channel bars 3 carried by wheels 4 that are adapted to travel on suitable tracks T. The channel bars 3 also support a frame-work composed of rear uprights 5, inclined angle irons 6 and diagonal braces 7.

A shaft 8 is journaled in suitable bearings in the side plates 6 and carries a sprocket wheel 9 around which passes a 45 chain 10 that also passes around a smaller sprocket wheel 11 secured to a shaft 12 also journaled between the side plates 2.

Two sets of eccentrics 13 and 14 are carried by the shaft 8, the eccentrics 13 being 50 displaced from the eccentrics 14 by about 180° so that when the eccentrics 14 are at the top of their travel, as shown in Fig. 2, the eccentrics 13 are at the bottom of their travel. The eccentrics 13 and 14 support 55 the upper ends of two sets of inclined grate

bars 15 and 16, the lower ends of which rest on a horizontal bar 17 mounted in bearings 18 that are carried by inclined bars 19 that extend out from the side plates 2.

The shaft 8 carries a worm gear wheel 20 which meshes with a worm 21 carried by a power shaft 22, the outer end of which carries a bevel gear wheel 23 for connecting the apparatus to any suitable source of power, not shown. The shaft 22 is mounted 60 in bearings 24 and 25 and carries near its lower end a worm 26 meshing with a worm wheel 27 that is secured to a shaft 28 carrying two sets of eccentrics 29 and 30 which are similar to the eccentrics 13 and 14 but 65 have a somewhat longer throw, in order to give the lower grate a longer movement than the upper grate. The eccentrics 29 and 30 carry two sets of grate bars 31 and 32, the lower ends of which rest upon a bar 70 33 that is mounted in bearings 34 carried by the side bars 6 of the frame.

A shaft 35 is journaled in bearings 36 carried by horizontal bars 37, and carries two sprocket wheels 38, while the shaft 12 at 80 the front of the machine carries two similar sprocket wheels 39, and two chains 40 extend around the sprocket wheels 38 and 39 and these chains carry a number of angle bars 41. An ash plate 42 extends underneath the chains 40 and the bars 41 and is adapted to receive ashes from the grate bars, the bars 41 acting as scrapers to draw the ashes to the front of the machine.

A hopper 43 is carried by the side plates 90 2 above the upper ends of the grate bars 15 and 16 and has a sliding gate 44 for regulating the amount of coal delivered to the grate bars, this gate 44 being adjustable vertically by means of two racks 45 meshing with pinions 46 carried by a shaft 47 which is provided with a suitable handle 48 outside of the hopper 43.

Each of the grate bars consists, as shown in Fig. 4, of a T-bar having its upper surface provided with serrations 49 and provided near its upper end with a bearing 50 which is circularly curved to receive its operating eccentric.

In operation, the stoker is rolled on the 105 tracks T into a furnace chamber, one wall of which is indicated at 51, Figs. 1 and 2. Fuel is placed in the hopper 43 and is allowed to drop on the upper grate bars and pass under the gate 44, the amount of fuel 110

so delivered being regulated by raising or lowering the gate by means of the handle 48. Power is applied to the shaft 22 through the bevel gear 23 or other desired power connections, and the shafts 8 and 28 are thus set in motion, carrying with them the eccentrics 13 and 14 and the eccentrics 29 and 30. The rotation of the eccentrics causes the grate bars to move lengthwise in opposite sets, the bars 15 moving forward while the bars 16 are moving backward and vice versa. Also, the bars 31 move forward while the bars 32 are moving backward and vice versa, and the upper ends of all the bars are given a vertical orbital movement by the eccentrics. This movement of the bars serves to push the fuel gradually down and over the full length of the grate bars, the movement of the bars being so regulated that the fuel is entirely consumed before it reaches the lower ends of the bars. The forward movement of the fuel may be, for example, from two inches to six inches per minute. The ashes drop off the lower ends of the bars 29 and 30 upon the plate 42 and are carried to the front of the machine by means of the scrapers 41. This operation continues as long as coal is supplied to the hopper 43, no attention being required after the gate 44 is once adjusted to admit the proper amount of coal.

The grates may be either inclined as shown in the accompanying drawing or may be level if desired, and the entire device may be made of any convenient size and proportions to adapt it for use in any type of steam generator or in accordance with the wishes of the user. The bars composing the grates are separated from each other by a suitable interval to allow for proper draft, this interval or offset being about one thirty-second of an inch.

The lower set of grate bars may be run at higher speed than the upper set in order 45 to advance the partly consumed coal more rapidly than the coal entering the stoker from the hopper 43.

It will be observed that the entire stoker mechanism is a self contained unit and that, 50 when the fire is to be drawn or the stoker moved for any purpose, it is only necessary to roll the stoker out from beneath the furnace which requires but little time and no disconnection of parts. My improved stoker 55 may therefore be used where there are a number of furnaces, only a few of which are required to be used at one time, the stokers being readily transferred from one furnace to the other. Where a battery of 60 stokers is employed there must also be several auxiliary furnaces in order to take the place of the regular furnaces which may be shut down for repairs or for other reasons. When my improved stoker is used with such 65 equipment, the auxiliary furnaces need not

be equipped with stokers but the stokers can be moved from one furnace to the other as circumstances may require.

A further advantage of my stoker is that the fire can be killed in a few minutes, it 70 being only necessary to draw the stoker from the furnace in order to stop the operation of the furnace, after which the fire may be extinguished or the stoker transferred to another furnace as may be desired. 75

While I have herein shown and described a preferred embodiment of my invention, it is to be understood that various changes in the form and arrangement of parts may 80 be made without departing from my invention. I therefore desire that no limitations be imposed on my invention except such as are indicated in the appended claims.

I claim as my invention:

1. A mechanical stoker comprising a plurality of grates, one grate being adapted to receive partially consumed fuel from another, each of the said grates being composed of a plurality of bars disposed side by side and divided into two sets of alternate bars, and means for moving the said sets of bars lengthwise in opposite directions, and for simultaneously imparting a vertical orbital movement to one end of each of said bars. 95

2. A mechanical stoker comprising a plurality of grates, one grate being adapted to receive partially consumed fuel from another, each of said grates being composed of a plurality of bars disposed side by side and divided into two sets of alternate bars, a shaft extending transversely to the said bars beneath one end of each of said grates, eccentrics carried by said shafts and supporting the said bars, certain of said eccentrics occupying different angular positions, and means for rotating said shafts and for thereby moving said sets of bars lengthwise, and raising and lowering the front 110 ends of said bars. 105

3. A mechanical stoker comprising two grates, one grate being adapted to receive partially consumed fuel from another, each of said grates being composed of a plurality of bars disposed side by side and divided into two sets of alternate bars, and means for moving the said sets of bars in opposite directions comprising eccentrics supporting the front ends of said bars, the eccentrics associated with the lower grate having a longer throw than the eccentrics associated with the upper grate, whereby the lower grate bars are given a longer movement than the upper grate bars. 115 120

4. A mechanical stoker comprising two grates inclined in the same direction with the upper end of one grate beneath the lower end of the other, so that the lower grate may receive partially consumed fuel from 130

the upper grate, each of said grates being composed of a plurality of bars arranged side by side and divided into two sets of alternate bars, and means for moving said 5 sets of bars simultaneously in opposite directions.

5. A mechanical stoker comprising a frame, wheels for transporting the said frame on tracks, two parallel shafts journaled in the said frame, a plurality of eccentrics carried by each of the said shafts, the alternate eccentrics extending in opposite directions from the said shafts, a plurality of grates, one grate being adapted to 10 receive partially consumed fuel from the other, each of said grates being composed of grate bars disposed side by side, each of the said bars having one end supported on one of the said eccentrics, and horizontal 15 bars carried by the said frame for supporting the ends of the said grates opposite to the said eccentrics.

6. A mechanical stoker comprising a

frame, wheels for transporting the said frame on tracks, two parallel shafts journaled in the said frame, a plurality of eccentrics carried by each of the said shafts, the alternate eccentrics extending in opposite directions from the said shafts, a plurality of grates composed of grate bars disposed side by side, each of the said bars having one end supported on one of the said eccentrics, horizontal bars carried by the said frame for supporting the ends of the said grates opposite to the said eccentrics, 35 an ash pan adapted to receive ashes from one of the said grates, and an endless scraper carried by the said frame and adapted to draw the ashes to the front of the machine. 40

In testimony whereof I, the said JAMES M. PORTER, have hereunto set my hand.

JAMES M. PORTER.
